UNITED STATES PATENT OFFICE.

IRA W. FOLTZ, OF CHICAGO, ILLINOIS.

FURNACE.

Original application filed October 16, 1920, Serial No. 417,443. Divided and this application filed September 17, 1923. Serial No. 663,177.

This application for patent is a division of patent application, Serial No. 417,443, "furnaces".

This invention preferably relates to a furnace of that general class where at least a part of the air supplied to the fuel is pre-heated. The purposes of the invention are to provide a practical design for use in connection with steam boilers and for rendering a furnace more efficient for heating the boiler, and incidentally preventing loss of fuel in the products of combustion.

These objects are accomplished by the use of certain air conduits in conjunction with reflecting pier formations, all of which are constructed within the brick setting surrounding the boiler.

By means of the piers the currents of hot air and gas are broken up by their direct impact upon the piers, and thereby an extensive admixture of the air and the gases is attained in the early stages of combustion.

This furnace is especially designed to burn with high efficiency and without smoke, coal that contains large quantities of volatile matter, and is the result of many years of experimenting in actual furnace practice in connection with steam boilers, with mechanical stokers as well as with hand-fired equipment. In constructing this furnace the following elements are carefully considered: (1) the kindling temperature of the gases of the coal; (2) the quantity of air required under average conditions of operation; (3) the time necessary to complete the process of combustion; (4) the dimensions of the firebox, combustion chamber, breeching and stack; (5) the movement of the current of hot air and gas necessary to cause the gas to properly combine with the oxygen of the air. By means of this furnace the gases produced from the burning coal are ignited near the point of their liberation, excess air can be eliminated by proper control of the ashpit doors or of the stack damper, and a fairly uniform temperature can be maintained throughout the furnace, and thereby all the combustible elements may be consumed, the quantity of ash and clinkers reduced to a minimum, the heating surfaces of the boiler kept clean, and the capacity and efficiency of the boiler greatly increased.

These objects are accomplished by the de-

vice shown in the accompanying drawing, in which—

Figure 1 is a longitudinal sectional view of the wall structure of a furnace constructed according to this invention and shows the boiler in side elevation. This view is taken on the line 1—1 Figure 2.

Figure 2 is a sectional plan view taken on the line 2—2 of Figure 1, but with the grate omitted.

The design shown in the drawings comprises a boiler 1 surrounded by the usual wall structure 2 but containing the piers 3 and 4 and the wing piers 5. The pier 3 is centrally located on the bridge wall 4.1, thus providing the two throats 6 and 7 opposite and in front of wing piers 5. These wing piers therefore provide reflecting surfaces at right angles to the currents of air and gas passing through the throats 6 and 7. Likewise the throat 8 between the wing piers 5 directs these currents against the face of pier 4 causing a second reflection and eddying of the gas and air mixture.

In the operation of the furnace the usual fuel bed is maintained on the grate. The bridge wall 4.1 and the pier 3 at the middle thereon are located at the rear of the grate at right angles with the lateral walls of the furnace. The throats 6 and 7 are made as small in area as is consistent with a proper and sufficient draft in the furnace. The bridge wall and the pier thereon are disposed at right angles to the general flow of the currents of air and gas in the furnace and thus give a direct impact to those currents as they impinge on the front face or surface thereof, whereby those currents are caused to rebound and eddy, and thereby the air and gases are commixed resulting in complete combustion of the gases. The wing piers 5 are also disposed at right angles to those currents and stand directly opposite and to the rear of the throats 6 and 7 in the bridge wall. After passing through the throats 6 and 7 these currents impinge on the front face or surface of wing piers 5 with a direct impact that causes them to rebound and eddy again and then flow through the single throat 8 between the wing piers 5, and from there on to pier 4, all of which movements in such currents tend to promote thorough and complete combustion of the combustible elements of the coal. The piers

3, 5 and 4 have still another important function. By reason of their formation the front face or surface of each pier operates as a reflector to the fire in the furnace, whereby 5 heat is reflected towards the front of the furnace resulting in an increased temperature in the grate region of the furnace and thereby creating a condition favorable for the burning of the gases as they are liberated 10 from the fuel and completely consuming them near the point of their liberation.

I claim:

1. A furnace comprising surrounding walls forming a fire-box and combustion chamber, a grate in said fire-box located above the level of the floor of said combustion chamber, a bridge wall located at the rear of said grate, a pier on said bridge wall near the middle thereof and extending from 15 the top thereof substantially to the roof of said furnace, the front surface of said pier being at right angles with the side walls of said furnace and the lateral sides thereof being parallel with the side walls of the furnace, and wing piers joined to the side walls of said furnace at a point rearwardly and equidistant from said bridge wall, said wing piers extending from the floor of said combustion chamber substantially to the roof 20 thereof, the front surface of said wing piers being at right angles with the side walls of said furnace, a pier located rearwardly from said wing piers near the middle of said combustion chamber and extending from the floor thereof substantially to the roof thereof, the front surface of said pier being at right angles with the side walls of said furnace. 25

2. A furnace comprising surrounding walls forming a fire-box and combustion chamber, a grate in said fire-box located above the level of the floor of said combustion chamber, a bridge wall located at the rear of said grate, a pier on said bridge wall near the middle thereof and extending from 40 the top thereof substantially to the roof of said furnace, the front surface of said pier being at right angles with the side walls of said furnace, a pier located rearwardly from said wing piers near the middle of said combustion chamber and extending from the floor thereof substantially to the roof thereof, the front surface of said pier being at right angles with the side walls of said furnace. 45

being at right angles with the side walls of said furnace and the lateral sides thereof being parallel with the side walls of the furnace, and wing piers joined to the side walls of said furnace at a point rearwardly and equidistant from said bridge wall, said wing piers extending from the floor of said combustion chamber substantially to the roof 50 thereof, the front surface of said wing piers being at right angles with the side walls of said furnace and the lateral sides thereof being parallel with the side walls of said furnace, a pier located rearwardly from said wing piers near the middle of said combustion chamber and extending from the floor thereof substantially to the roof thereof, the front surface of said pier being at right angles with the side walls of said furnace. 55

3. A furnace comprising surrounding walls forming a fire-box and combustion chamber, a grate structure in said furnace located above the normal floor level of said combustion chamber, a bridge wall located at 70 the rear of said grate, a pier on said bridge wall near the middle thereof and extending from the top thereof substantially to the roof of said furnace, the front surface of said pier being at right angles with the side walls of said furnace and the lateral sides thereof being parallel with the side walls of said furnace, and wing piers joined to the side walls of said furnace at a point rearwardly and equidistant from said bridge 75 wall, said wing piers extending from the floor of said combustion chamber substantially to the roof thereof, the front surface of said wing piers being at right angles with the side walls of said furnace, a pier located rearwardly from said wing piers near the middle of said combustion chamber and extending from the floor thereof substantially to the roof thereof, the front surface of said pier being at right angles with the side walls of said furnace. 80

Signed at Chicago this 14th day of September, 1923.

IRA W. FOLTZ.
